(57) **CLAIM**

We claim the ornamental design for a fishing gutting scissors, as shown and described.

DESCRIPTION

FIG. 1 is a front perspective view from above of the claimed design;

FIG. 2 is a left side view of the claimed design of FIG. 1; FIG. 3 is a right side view of the claimed design of FIG. 1; FIG. 4 is a front view of the claimed design of FIG. 1; FIG. 5 is a rear view of the claimed design of FIG. 1; FIG. 6 is a top view of the claimed design of FIG. 1; FIG. 7 is a bottom view of the claimed design of FIG. 1; and, FIG. 8 is a rear perspective view from above of the claimed design of FIG. 1.

The features of the fishing gutting scissors drawn in broken line depict ornamental surface decoration that forms no part of the claimed design.

1 Claim, 6 Drawing Sheets
